Primary Examiner — Samantha Wood*Assistant Examiner* — Vanessa Martinez(74) *Attorney, Agent, or Firm* — RatnerPrestia(57) **CLAIM**

The ornamental design for a light for motor vehicle, as shown and described.

DESCRIPTION

FIG. 1 is a perspective view of a light for motor vehicle showing my new design;

FIG. 2 is a front view thereof;

FIG. 3 is a right view thereof;

FIG. 4 is a left view thereof;

FIG. 5 is a top view thereof; and,

FIG. 6 is a bottom view thereof.

The broken lines in the drawings show portions of the light for motor vehicle that forms no part of the claimed design.
